UNITED STATES PATENT OFFICE.

JOHN A. JAMES, OF SAILES, LOUISIANA.

CLEVIS.

Application filed August 20, 1923. Serial No. 658,412.

This invention relates to improvements in clevises which are adapted to be used in combination with the draft beams of plows.

The principal objects of the invention are to provide clevises of novel construction which are capable of being quickly adjusted at the beginning of plowing operations for the purpose of gauging the depth of the plowshares in the soil; to provide clevises to which such necessary adjustments may be made in a simple and convenient manner without the necessity of special tools; and, to provide clevises which will be simple and cheap to manufacture, and which may readily be installed upon plows already now in use.

Other objects and advantages will appear in the following detailed description taken in connection with the accompanying drawing, forming a part of this specification, and in which drawing:

Figure 1 is a fragmentary side elevation of a plow equipped with my improved adjustable clevis.

Figure 2 is an enlarged side elevation of the clevis attached to a fragment of the plow beam, and showing in dotted lines the position assumed by a novel coupling device when being removed from or adjusted to the clevis.

Figure 3 is a transverse section, on a slightly enlarged scale, taken on the line 3—3 of Figure 2.

Figure 4 is a transverse section, on a slightly enlarged scale, taken on the line 4—4 of Figure 2.

Figure 5 is a detail perspective view of a novel coupling device which may be used in combination with the improved clevis.

In the accompanying drawing, wherein for the purpose of illustration is shown but the preferred embodiment of this invention, and wherein similar reference characters designate corresponding parts throughout the several views the letter A indicates a plow of any approved construction; B clevis plates; and C, a coupling device which may be used in combination with the clevis plates B.

The clevis plates B are adapted to be carried by the draft beam 10 of the plow A on the opposite sides of the forward end thereof, each plate comprising a main body portion 11 and a head 12. These companion plates may be pivotally or axially connected, as at 13, to the forward end of the draft

beam 10, said pivotal connection being herein shown as consisting of a headed bolt 14 extending transversely through the companion plates B and the draft beam 10 and provided at the one end with screw threads upon which may be fitted a washer 15 and a suitable lock nut 16. Forwardly of the pivotal connection 13 the plates B may each be provided with a plurality of spaced perforations 17 equi-distant from the pivotal connection 13, any one of which perforations may be aligned with a horizontal perforation 18 in the forward end of the draft beam 10, and may be secured in such an adjusted position by a suitable locking device 19 herein shown as consisting of a headed bolt 20, a washer 21, and a lock nut 22 threaded on the one end of the bolt 20. It can readily be seen that by removing the locking device 19 and swinging the companion plates B upon the pivotal connection 13 a vertical adjustment of the clevis plates B may be secured with respect to the longitudinal axis of the draft beam 10.

The heads 12 of each of the companion plates B are each provided with a vertical elongated slot 23 and a plurality of spaced recesses 24 extending forwardly in angular relation from the slot 23, preferably in diagonal planes, each recess 24 preferably terminating in a substantially circular enlargement 25.

Referring now to the novel coupling device C, which may be used in combination with the clevis plates B, the same preferably comprises a stem 27, the forward end of which may be hooked as at 28 for the purpose of securing the lap-ring or other fastening device of a single tree thereto. The opposite end of the stem 27 may be provided with a transversely extending cross piece 29 thereby providing arms 30 which project beyond the sides of the stem 27. These arms 30 may have the sides thereof flattened, as at 31, and the opposite ends rounded, as at 32, thereby providing arm members which will be polygonal in cross section.

When in use, the arms 30 of the coupling device C are adapted to be positioned in the elongated vertical slots 23, and the coupling device C may be moved longitudinally of the slot 23, that is vertically with respect to the beam 10 in order that various adjusted positions thereof may be obtained. When it is desired to fit the coupling device C in any

of the companion recesses 24 the same may be caused to enter the companion recesses 23 by holding in a position similar to that shown in dotted lines in Figure 2 of the drawing 5 so that the flattened sides 31 of the arms 30 will be parallel with the recesses 24 and the hook C may then be drawn forwardly in the desired companion recess 24 until it reaches the substantially circular enlargement 25 10 which is at the terminal of each recess 24. The coupling device C may then be turned to a position similar to that shown in full lines in Figure 2 so that the rounded ends 32 of the arm 30 will engage the walls of the 15 circular enlargement 25 which will effectively prevent the withdrawal or removal thereof until again turned to a position similar to that shown in dotted lines in Figure 2 of the drawing.

20 From the foregoing description it can be seen that a novel clevis device has been provided which may itself be adjusted vertically with respect to the longitudinal axis of the beam and is provided with novel means 25 whereby a coupling device which is associated therewith may be selectively adjusted, with a minimum amount of time, and which adjustment may be without the use of special tools. It will also be apparent that due 30 to the simple construction of the devices they may be manufactured and sold at a reasonable cost.

Changes in details may be made to the form of the invention herein shown and de- 35 scribed without departing from the spirit of the invention or the scope of the claim.

I claim:

As an article of manufacture a clevis including a pair of connected spaced plates having transversely aligning substantially 40 vertical slots therein, each plate having a plurality of substantially parallel downwardly sloping slots leading from the vertical slot and arranged at an acute angle thereto, each of said downwardly sloping 45 slots having an enlarged socket at its lowermost end, the width of said downwardly sloping slots being less than the width of the vertical slot, and the width of the enlarged socket of each of the downwardly 50 sloping slots substantially corresponding to the width of the vertical slot, and a T-shaped coupling device including a shank portion adapted to be positioned in the space between the plates and including cross 55 arms at the rear end of said shank portion, which cross arms are of greater width than thickness, the width of said arms being greater than the width of the downwardly 60 sloping slots and the thickness of said arms being less than the width of the downwardly 65 sloping slots whereby the coupling device will have to be tipped at a predetermined angle to permit the cross arms to slip from the vertical slots through the downwardly 70 sloping slots into the socket ends of the downwardly sloping slots, said cross arms when disposed in the enlarged socket ends of said downwardly sloping slots permitting pivoted movement of the coupling device in a vertical plane.

JOHN A. JAMES.
